(57) **CLAIM**

The ornamental design for a reusable candle vessel, as shown and described.

DESCRIPTION

FIG. 1 is a top, front perspective view of a reusable candle vessel showing our new design;

FIG. 2 is a front elevation view thereof;

FIG. 3 is a cross-sectional side view thereof which is taken about line 3-3 in FIG. 2; and,

FIG. 4 is a cross-sectional view thereof corresponding to FIG. 3, and which shows an alternative flexed state of a bottom of the reusable candle vessel.

The stippling shown in FIGS. 1-4 is for the purpose of illustrating claimed portions of the reusable candle vessel that are made from a flexible material, and the claimed outer cylindrical portion of the reusable candle vessel that is not stippled illustrates a portion of the candle vessel that is made from a material that is more rigid than the flexible material. The uniform broken line showing in FIGS. 1-4 is for the purpose of illustrating a cap of the reusable candle vessel and forms no part of the claimed design.

The dot-dash broken line showing in the cross-sectional views of FIGS. 3 and 4 is for the purpose of illustrating environment, namely a full candle wax insert in FIG. 3 and a remnant of the candle wax being displaced by the flexure of the bottom of the candle vessel in FIG. 4, and this illustrated environment forms no part of the claimed design.
